UNDERFRAME CONSTRUCTION FOR
RAILWAY CARS

Argyle Campbell, Chicago, Ill., assignor to Enterprise Railway Equipment Company, Chicago, Ill., a corporation of Illinois

Application August 23, 1930, Serial No. 477,332

36 Claims. (Cl. 105—228)

My invention relates to improvements in underframe construction for railway cars.

An object of my invention is to strengthen the car underframe adjacent the body bolster whereby those car body members which establish contact with the truck parts will be rigidly mounted and secured against disruption from longitudinal, transverse, weaving or eccentrically applied strains.

10 The points of contact between the trucks and body parts in the conventional design of railway car are the center plate and side bearing members, the former being adapted to transmit the weight of the car to the truck and constituting 15 the main connection through which draft and buffing strains are transmitted from the car body to the trucks and the side bearings being adapted to function in supporting the body as the car is displaced from a vertical position, as, for instance, when the weight of the car body is 20 concentrated on one side, due to elevation of outer rail when rounding curves on the track.

The fact that the centerplate members are disposed at an appreciable distance above the center of gravity of the trucks results in eccentric loading of the body bolsters and truck parts on the application of strains caused by relative motion between body and truck parts, such strains being initiated by the starting or stopping 30 of trains or the sudden application of the air brakes, a condition which results in loosening of the attaching rivets and twisting of the bolster parts.

35 The adoption of cars of heavier tonnage with increased dimensions of height, length and longer truck centers has resulted in higher centers of gravity for the loaded cars and greater swing of the trucks, which has further accentuated the need for a rigid, well-braced construction capable of preventing separation of the center plate from the car body and maintaining the bolsters against twisting under draft and side bearing strains.

40 A particular object of my invention is to remedy the existing weakness and effect an improved connection between the centersill structure and the side bearing members, whereby strains are transmitted from the body of the car to the side bearings in a direct manner.

45 Another particular object of my invention is to provide an improved construction which strengthens the side bearing members of the car and bolster construction identified therewith against twisting strains.

50 Still another particular object of my invention

is to provide a reinforcing structure for the body bolster of a railway car, which makes a rigid connection between the body bolster, the centersill and body centerplate, and between the centersill and body side bearings.

5 A more specific object of my invention is to provide a bolster strengthening member incorporating integral wall members for connection with diagonal bracing means extending from the outer corners of the car to the junction of the body bolster and centersill.

Another and more specific object of my invention is to provide a bolster stiffening member which will have a portion extending upwardly above the centersill structure to strengthen the 15 body bolster against vertical displacement relatively to the centersills.

My invention further resides in certain features of construction and detail of parts such as will be more fully pointed out hereinafter and 20 claimed.

For further comprehension of my invention reference may be had to the accompanying drawings, wherein

Fig. 1 is an elevational transverse sectional view 25 of a portion of a hopper car taken adjacent to the body bolster and showing so much of the car construction as is necessary to illustrate my invention;

Fig. 2 is a plan sectional view substantially on 30 the line 2—2 of Fig. 1 of that portion of the car illustrated in Fig. 1, together with construction identified with the diagonal bracing and corner of the car;

Fig. 3 is a vertical longitudinal sectional view 35 substantially on the line 3—3 of Fig. 1;

Fig. 4 is a plan view of the bolster bottom member proper showing the same detached from the car;

Fig. 5 is an end elevational view of said bolster 40 bottom member as viewed on a line 5—5 of Fig. 1;

Fig. 6 is an elevational transverse sectional view 45 of a portion of a car showing my improvements applied to a modified form of car having a comparatively shallow bolster of the double web type;

Fig. 7 is a plan view of that portion of a car illustrated in Fig. 6, certain of the parts being broken away to better illustrate the construction;

Fig. 8 is a view taken similarly to Fig. 6 of still 50 another modification, showing a different embodiment of my invention as applied to a car having a relatively deep centersill and body bolster construction, this type of construction generally being employed in dump cars having the floors ele- 55

vated a sufficient distance to discharge the load outwardly above the truck parts to the sides of the track; and

Fig. 9 is a sectional plan view of that portion of the car illustrated in Fig. 8, said view being taken on a line 9-9 of Fig. 8.

Referring now to the construction illustrated in Figs. 1 to 5, inclusive, wherein my improved construction is shown as applied to a car of the hopper type.

In said drawings, 10 indicates the rails on which the car is adapted to have movement; 11 the wheels of the truck; and 12 the truck bolster having an integral centerplate bearing 13 and side bearings 14-14 on each side of the centerplate, said bolster having a swiveling movement with the body of the car about the axis of center pin 15.

The centersill structure is indicated generally by the reference character A, and includes a pair of flanged members 100-100, each member having a vertical web section 101, an inwardly directed upper flange 102 and lower marginal flanges extending respectively inwardly and outwardly, as indicated at 103 and 104, respectively. The respective members 100 are spaced apart an appreciable distance and united by a cover plate 105 of appreciable width. Interposed between said pair of centersill members 100 and extending lengthwise of the car is an integral bolster spacing member indicated generally by the reference character B.

Extending transversely of the car and across the plane of the centersill is a vertically extending body bolster member C, which includes a vertical web plate section 106 extending from side to side of the car and having a rectangular section coped out as indicated at 107 to straddle the centersill structure and present sections 108-108 on each side of the centersill. The web plate adjacent its upper portion is formed to present an inclined flange 109 for attachment with the hopper sloping floor 110. The body bolsters are extended outwardly to each side wall 111, one of said side walls only being indicated in Figs. 1 and 2, and connected therewith by a plurality of angle shaped connections 112. The lower margin of the bolster web plate is reinforced by oppositely disposed angle members 113 and 114, respectively, the former preferably extending from the side wall to the centersill and the latter terminating short of the centersill as indicated at 115. These angle members are disposed with one flange overlying and secured to the bolster web plate as indicated at 116 and having their adjacent flanges outstanding from the bolster web plate and constituting bolster marginal reinforcing means. The angle members are preferably disposed to extend upwardly from the centersills, thereby providing upwardly extending marginal portions on each side of the centersill. Cooperating with said bolster outstanding flanges is a bottom plate member 117 extending inwardly from the car side wall lower marginal member 118 to a location approximately midway between the side wall and centersill.

Extending across the centersills and overlappingly related with said bolster bottom plate 117 and the outstanding flanges of the respective bolster bottom angles 113 and 114 is the bolster bottom member D. Said member D preferably consists of a one-piece member having integrally formed therewith a centerplate 119 and a pair of side bearings 120, the latter being respectively disposed on opposite sides of the centersill and

spaced an appreciable distance therefrom. The member D, which is disposed in alignment with center filler B, bears directly against the same, as indicated at 121, and is united thereto by rivets 122 which also extend through the flanges 103 of the centersill. The member D extends upwardly and outwardly from the opposite sides of the centersill at an angle to correspond to the upward inclination of the respective bolster sections, and extends beyond the integral side bearings to overlap and unite with the bottom plate 117 and the outstanding flanges of the bottom angles, as above mentioned.

The bottom member D gradually diminishes in width from the centersill to its respective outer ends and is reinforced longitudinally and transversely of the car by integral depending flanges 123, 124, 125, and 126. The flanges 123 and 125 together define a rectangular shaped reinforcement for the body portion adjacent the centerplate section against bending. The flanges 126, Figs. 4 and 5, adjacent the side bearings, are increased in depth sufficiently to make an integral connection with the side bearing sections 120, and said deepened portion of the flanges 126 and 25 the side bearing portion 120 are further united by an integral wall section 127 extending at an angle substantially normal to the plane of the main body portion. The wall section 127 is provided with a plurality of recesses 128 adapted to accommodate the heads 129 of rivets which fasten a wear plate 130 to the side bearing sections 120. Rearwardly of flange 125 and formed integrally therewith, the member D is further provided with an extension 131 adapted to be 35 united by connecting rivet 132 with a rearwardly disposed extension 133 of the bolster center filler B. The extension 131 is braced to the rear depending flange 125 by a series of ribs 134.

Extending across the plane of the centersill and above the bolster bottom member B is a combined reinforcing and connecting member E, which includes a central section of angular form defined by a vertical wall 135 and a horizontally extending wall 136. The wall 135 overlies and is secured 45 to the bolster web 106, and the wall 136 overlies and is secured to the flat upper portion of the centersill. Outstanding from said central section of member E are side sections 137-137, respectively disposed on opposite sides of the centersill, but inasmuch as the construction is the same on each side of the centersill the description herein will be confined to only one side.

The side section 137 includes integral walls 138, 139 and 140, respectively overlying the centersill 55 web, the bolster web plate and the bolster bottom member, and thus forming a three-way bracket connection lying in the angle defined by the said three members. The section 137 is extended outwardly to a location immediately above the side bearing and is there formed with an integral bracket portion 141 having a transverse vertical wall 142 cooperating with and secured to the outstanding flange 143 of a vertical bolster stiffener 144. Said bracket portion 141 is extended beyond 60 the associated outstanding flanges of the bolster bottom angles to brace the bolster bottom member at the side bearing 120. Further reinforcement is provided for the said bracket portion 141 by an outstanding bracing wall 145 extending 70 in a direction normal to the plane of the bottom member and substantially in alignment with the general direction of the web section 127 of the side bearing 120. The said wall 145 is continued upwardly and inwardly towards the upper corner 75

of the centersill structure to present wall sections 146 and 147, thereby integrally uniting the respective walls 138, 139, and 140, and completing therewith a pan-shaped bracket adapted to 5 brace the bolster in all directions.

The wall 147 is extended outwardly from the bolster lengthwise of the car and secured to a horizontally disposed brace member 148 which leads diagonally towards the corner of the car 10 and is united with the car structure at the junction of the end sill 149 and side sill 150. The respective outstanding walls 138, 140 and 146 are braced relatively to the wall section 139 by triangular connecting bracing ribs 151, Figs. 15 1 and 3. The plane of wall 138 is extended rearwardly of the body bolster across the plane of the bolster web to provide on the opposite side of the section 137 an additional wall 152 for attachment with the centersill. This wall 152 in 20 conjunction with walls 138 and 139 thus provides a substantially T-shape section. Extending from a point adjacent the junction of the central portion and each side section 137, there is disposed an integral upwardly extending angular bracing section having one wall 153 extending lengthwise of the car and having the adjacent wall 154 overlying the bolster web 106 and secured thereto by rivets 155, said rivets also embracing horizontally and vertically disposed stiffener members 156 and 157 disposed 25 on the opposite side of the bolster web. The member 156 is extended across the plane of the centersill and riveted to the vertical wall of the central section 135 and also to the upper portion 30 of the center sill, said last named connection being indicated at 158. The vertical member 157 is extended upwardly beyond the termination of the member E and continues the bracing effect thereof to the top of the bolster web plate. Adjacent its lower portion the vertical stiffener 157 is crimped at 159 to overlap the vertical flange of member 156.

At each side bearing, on the side of the bolster opposite to the member E, there is cooperating bracing means including a bracket F and a bracing stiffener 160, said stiffener having a wall 161 overlying the bolster web plate and a flange 162 outstanding therefrom. The bracket F includes a wall portion 163 overlying the bolster vertical section and united therewith and with the member E by rivets 164, said member also including a section 165 extended beyond the outstanding flange of the bolster bottom member E. The sections 163 and 165 are braced to 50 each other by angularly disposed walls 166 and 167, the former overlying and secured to the outstanding wall 162 of the bolster stiffener 160 and the latter being disposed substantially normal to the main body section of member D. The walls 166 and 167 are integrally united adjacent their upper portions by a connecting wall 168.

The saddle effect of the integral central and side sections of the member E in connection with the bolster center filler B and the bottom member D cooperate to form a continuous connection of great strength extending from side bearing to side bearing, and the rigid attachment of the said member E with the centersill webs effectively overcomes any tendency to twisting or lengthwise separation between bolster and centersill. The cooperation between the members E and F on the opposite sides of the bolster web also insure the necessary strength to maintain the side bearings against horizontal displacement due to uneven application of loads on the

side bearings when the truck is displaced to a position as indicated by conventional dotted lines at 169 in Fig. 2 as the car moves around curves.

In the modification shown in Figs. 6 and 7, my improvements are shown as applied to a car having a shallow type of bolster construction. In said drawings only the construction on one side of the centersill is shown, but it will be understood that the construction will be duplicated on the opposite sides of the center line of 10 car.

In this modified structure 200 indicates one of the centersill vertical members, 201 the centersill cover plate, 202 the centersill bolster filler and 203 the bolster centerpin, and 204 the bolster 15 bottom plate extending across the centersill to connect with a pair of bolster sections 205. The bottom plate 204 in the plan view is cut away to better illustrate the parts, but it will be understood that it extends clear across the centersill and unites with a corresponding pair of bolster sections on the opposite side of the centersill. Each bolster section 205 includes a vertical web 206 and upper and lower outstanding flanges 207 and 208, respectively. The bolster 25 sections are spaced apart by a combined filler and reinforcing bracket 209 which has a substantially vertical web section 210 and outstanding flanges 211 for connection with the vertical web 206 of the respective bolster sections. 30

Extending transversely across the centersill is the bottom member 212 which is formed with a body portion 213 adapted to overlie the bolster bottom member 204, said bottom member 212 incorporating therewith an integral centerplate 35 portion 214 and integral side bearing portions 215. The centerplate portion is reinforced at its margins by depending flange sections 216, 217 and 218, and intermediately by a longitudinally extending flange 219. The said centerplate and side bearings are adapted to respectively cooperate with companion bearing members formed on a truck bolster 220. The bottom member 212 is formed with an opening 221 for the purpose of economizing in weight. Extending rearwardly of the bolster section the member 212 is formed with a rearwardly extending horizontal portion 222 connected with the bolster center filler 202 by rivets 223.

The respective bolster sections 205 on the opposite sides of the centersill are connected by a transversely extending top cover plate 224, said plate being shown as partially cut away in Fig. 7.

A member 225 connects each said bolster section with the centersill. This member has a body 55 section 226 overlying and secured to the web 205 of the bolster section. The member 225 extends from the centersill to a position over the side bearing and has integral wall sections 227, 228, 229, 230, and 231 outstanding from its web 205. 60 These wall sections cooperate to form a continuous marginal reinforcement for the member and define, with the body section 226, a pan-shaped member lying in the angles between the vertical centersill, the bolster vertical wall section and the respective top and bottom bolster members. The outstanding wall 230 operates as a brace above the side bearing horizontal and vertical portions of the member. Cooperation between the bolster filler bracket 209 and the respective members 225 on the pair of spaced bolster sections is effected by connecting rivets 231 which unite the body section 226, the bolster web 205, and the walls 211. Each said member 225 is provided with an inwardly extending flange 75

232 for attachment with the centersill structure and forms, in combination with the body section 226 and the flange 227, a T-shape connection between the centersill and bolster section.

5 In the modification shown in Figs. 8 and 9, my improvements are shown as applied to a car having a relatively deep centersill of built-up construction. In this construction the centersill is shown as including a web plate 300, top angles 10 301, bottom angles 302, and top cover plate 303. Interposed between the centersills is the bolster center filler 304 having means for the reception of centerpin 305. Outstanding from said centersill on each side, there are bolster sections 306 15 each preferably formed of built-up I-section and having the lower portion inclined upwardly and outwardly. Each bolster section includes a web 307, angle-shaped members 308 on the opposite sides thereof adjacent the upper margin, 20 and bottom members 309 and 310, respectively disposed on opposite sides of the bolster web and united therewith. The member 309 is extended from immediately adjacent the centersill and member 310 terminating an appreciable distance 25 from the centersill as indicated at 311. Connection with the bolster section across the plane of the centersill is effected by top and bottom members 312 and 313, respectively, said bottom member 313 including in an integral unit a body 30 section 314, centerplate 315 and side bearings 316. The body section 314 is reinforced by integral depending ribs 317, 318, 319 and 320. Above the side bearings, the bolster is rigidified by stiffeners 321 disposed on opposite sides of the 35 web and each formed of angular shape with one wall 322 overlying the bolster section and the other wall 323 outstanding therefrom.

A connecting and bracing member 324 is disposed in overlying relation with the bolster section 40 and secured thereto by a wall section 325, said wall section also being disposed in overlying relation with the bolster top and bottom angle members. The bracing member 324 is provided with integral outstanding walls 326, 327, 328, 329, 45 330 and 331, cooperating with the web section 325 to form a box-shape member presenting a continuous marginal reinforcement. The walls 326, 327, and 328 are respectively united with the bottom member, the centersill and the bolster top 50 member. The wall 329 is united with the outstanding flange of the bolster stiffener 321, and walls 330 and 331 act as marginal reinforcements for the edge of the member 325 to provide reinforcement from the outer edge of said member 55 to a location adjacent the upper portion of the centersill and bolster. The plane of wall 326 is continued beyond the wall 310 and extended as at 332 to brace the side bearing member. The extended portion 332 is itself braced relatively 60 to the main body portion by an outstanding wall member 333 disposed substantially normal to the upwardly inclined portion of the bolster bottom member. The walls 329, 330, 333 and 332 thus cooperate with the rear wall portion 325 to form 65 a box-shaped bracket.

Disposed on the side of the bolster web plate 306 opposite to the said member 324 is a side bearing bracket member having a wall section 334 overlying the bolster web 306 and having a 70 series of wall sections 335, 336, 337 and 338 outstanding therefrom. These walls, in their general formation and relation to the associated car parts corresponding to the respective walls 329, 330, 333 and 332 of member 324. The bolster member 313 is offset at 339 adjacent its outer

end, and disposed between said offset portion and the bolster bottom angles is a bolster bottom cover plate 340 which cooperates with the said bottom member 313 to provide adequate sectional area for the bolster bottom chord throughout the full extent of the bolster.

I claim:

1. In a railway car including an upstanding centersill extending lengthwise of the car, an upstanding bolster member extending outwardly 10 from the centersill, a bolster bottom member extending flatwise beneath said centersill and bolster members; an integral connecting member having walls adapted to overlie and respectively connect with each of said three members, 15 and ribbing means extending at an angle to each of said three walls and integrally uniting the same.

2. In a railway car including a centersill structure having walls of appreciable depth, a body 20 bolster section extending outwardly from said centersill, side bearings carried by the bolster section, a bracing and connecting member connected between the bolster section and the centersill wall, said member being extended to a 25 location adjacent the side bearing and affording a supporting brace for said side bearing.

3. In a railway car including a centersill structure having walls of appreciable depth, a body bolster section outstanding therefrom on each 30 side of the centersill, side bearings carried by said bolster on the respective sides of the centersill, bracing means disposed above said side bearings for bracing the bolster above said side bearings, said bracing means being disposed on opposite sides of the bolster section, with bracing means on one side of the bolster section extending continuously across the centersill between the side bearings and provided with integral connecting walls attached to the vertical walls of 40 the centersill structure.

4. In a railway car, the combination of a centersill having side walls of appreciable depth, a bolster web extending transversely thereof, side 45 bearings carried by the bolster and spaced appreciably from the centersill on each side thereof, bracing means overlying and secured to the web of the bolster on one side thereof, and having flanged sections respectively overlying the upper portion and side walls of the centersill, 50 said bracing means having a body portion extending outwardly to a location above the side bearings and formed with a section adapted to brace said side bearings on one side of the bolster web, and bracket means on the side of the bolster 55 web opposite to said bracing member adapted to cooperate therewith for bracing the side bearing on the opposite side of the bolster web.

5. In a railway car, the combination of upstanding longitudinal centersill and upstanding 60 transverse bolster members, a bottom member extending flatwise beneath said centersill and bolster members, said bottom member incorporating therein integral centerplate and side bearing members and having depending integral 65 ribs extending continuously from side bearing to side bearing and adapted to brace the said bottom member across the plane of the centersill, said depending ribs being spaced outwardly beyond and independently of the center plate.

6. In a railway car, the combination of a centersill structure, a body bolster including a transversely extending section on each side of the centersill structure, means for uniting said bolster sections below the centersill, said means 75

having a centerplate and side bearings formed integrally therewith, the side bearings being spaced outwardly appreciably from the centerplate on each side thereof, and bracket means disposed in the plane of the centersill on each side thereof and secured to the centersill and bolster section, said means being extended outwardly to a location adjacent the side bearings.

7. In a railway car, the combination of a longitudinally extending centersill structure, including members spaced transversely of the car and a center filler interposed between said sills, bolster sections on the outer sides of said centersills substantially in alignment with the center filler; a stiffening and connecting member uniting each transverse section of the bolster with the centersill and center filler, said stiffening member extending generally from a location adjacent the top of the centersill and leading outwards in a downward direction, and formed with integral flanges lying on opposite sides of the bolster section, said integral flanges being united to the center filler and centersill webs.

8. In a railway car, the combination of centersill sections spaced transversely from each other and having a filler member interposed therebetween, transversely extending bolster sections on the opposite sides of said centersill substantially in alignment with the center filler, each bolster section including an upstanding portion and lower marginal flanges outstanding therefrom, side bearings beneath said lower marginal flanges disposed on the respective sides of the centersill and spaced outwardly therefrom, connecting means between the centersill and bolster sections, including a bracket member having a body section overlying and secured to the bolster web, flanges outstanding from the body section of the bracket and respectively secured to the centersill sections, the filler member and the lower marginal flanges of the bolster, and integral reinforcing rib means connecting said respective flanges, said reinforcing rib means being integrally united with the respective flanges and extending from a location adjacent the upper portion of the centersill and leading in a general direction towards the side bearings.

9. In a railway car bolster construction including a centersill structure and side bearings on each side of the centersill spaced outwardly from said centersill, the combination of a longitudinally extending bracing member extending from a corner of the car to a location adjacent the junction of the body bolster and centersill; a connection between said corner brace and body bolster, said connection including a body section secured to the bolster and extended lengthwise of the body bolster and terminating adjacent the side bearing to constitute a bracing means for the bolster adjacent said side bearing, said connection having integral wall sections extending lengthwise of the car vertically and horizontally and respectively secured to the centersill and corner brace.

10. In a railway car, the combination of a centersill, body bolster, end sill and side sill, a diagonally extending bracing member extending from a location adjacent the junction of the end sill and side sill to a location adjacent the junction of the centersill and bolster; a connection member at the junction of said diagonal member and centersill having integral wall sections respectively secured to the centersill, the body bolster and the diagonal brace member, said integral wall section being disposed horizontally and substantially

in alignment with the upper portion of the centersill.

11. In a railway car, the combination of a centersill, body bolster, side sill and end sill, a diagonally extending brace extending from a location adjacent the end sill and side sill to a location adjacent the junction of the body bolster and centersill; a connecting element between said diagonal brace and the centersill and body bolster, said element comprising a flanged section overlying and secured to the centersill and a body section secured to the body bolster, and horizontally extending wall sections overlying and secured to the diagonally extending brace.

12. In a railway car, the combination of a centersill structure defined by a pair of flanged members having vertical webs and a surmounting cover plate; a bolster section extending transversely above the centersill and to the sides of the vertical webs of said centersill, means connecting said centersill structure and bolster section, said means including a bracket member having a body portion overlying and secured to the bolster section, and integral flanges outstanding therefrom and respectively overlying and secured to the adjacent centersill vertical web and said cover plate.

13. In a railway car construction, the combination of a centersill structure having an upper section of extended width and substantially vertical webs, a transversely extending body bolster wall section extending above said centersill structure and to the sides thereof, and having a lower marginal reinforcement outstanding from the bolster web section; side bearings disposed below the bolster lower marginal reinforcement and spaced appreciably from the centersill; a reinforcing member having a body portion overlying and secured to the bolster web section, integral wall sections outsanding from the said body portion and respectively secured to the bolster marginal reinforcement, the centersill vertical web section and the upper section of the centersill, and additional integral ribs extending from a location adjacent the side bearings toward the upper portion of the centersill.

14. In a railway car, the combination of a longitudinal centersill structure, a bolster web extending transversely across the plane of the centersill above the same and having sections on either side thereof, means for providing a rigid connection between said bolster web and centersill, said means including an integral member having a body portion overlying the bolster web and having integral flange sections respectively overlying and secured to the upper portion and the vertical portion of the centersill.

15. In a railway car bolster construction, the combination of a centersill structure, a bolster web plate extending outwardly from each side thereof and having an outstanding lower flange member, side bearings disposed below said lower flange member at an appreciable distance from the centersill, a connecting member interposed in the angle defined by the centersill and said lower flange member, said connecting member having integral wall portions respectively united with the said lower flange member and with the centersill and extending downwardly from a location adjacent the upper part of the centersill towards the side bearing, said connecting member having an integral section extending upwardly above the centersill and overlying the bolster to brace the bolster against lengthwise displacement.

16. In a railway car, the combination of a

- centersill having an upper portion of appreciable depth and vertical web sections and a top cover plate, a transversely extending bolster member extending above and to the sides of the sill, a 5 bracing member extending between the bolster member and the centersill and incorporating in a one-piece unit flanged section respectively secured to the bolster web and overlying and respectively secured to the centersill web and centersill top cover plate, said bracing member also 10 embodying an integral upward extension having one flange overlying and secured to the bolster web and having an adjacent flange extending lengthwise of the centersill to brace the member 15 relatively to the centersill.
17. In a railway car, the combination of a centersill having upstanding web sections, transversely extending upstanding bolster wall sections lying at the respective sides of said sill and 20 having a portion extending above the top of the centersill, said bolster wall sections having an outstanding lower marginal reinforcement, a reinforcing member having a body section overlying and secured to the bolster upstanding section, said reinforcing member having integral 25 wall sections outstanding from its body section and respectively secured to the bolster lower marginal reinforcement and the centersill web, said reinforcing member also having integral sections extending upwardly above the level of 30 the centersill and inwardly above the top of the centersill.
18. In a railway car, the combination of centersills, a body bolster web section having an articulated portion formed to straddle the centersill and having wall sections at the respective sides of the centersill; connecting means between the centersill and body bolster web section, including a body section secured to the body bolster web and extended above the centersill and having portions 35 lying adjacent the sides of the centersill, integral flange sections extending from said body section and respectively overlying the upper portion of the centersill and the vertical side portion of said centersill on each side thereof, said last named flanged portion being disposed on opposite sides of the bolster web section and secured to the centersill on either side of the bolster web. 40
19. In a railway car, the combination of a centersill and bolster sections on the opposite sides thereof, means for uniting said bolster sections and centersill, said mean including a bracket member overlying the bolster web section and secured thereto, said member having integral flanges disposed on opposite sides of the bolster 45 section, each said respective flange being united with the centersill.
20. In a railway car, the combination of a centersill and bolster sections on the opposite sides thereof, each said bolster section including a web member and outstanding marginal reinforcing wall sections; means for uniting said bolster sections to the adjacent centersill, said means including a connecting and reinforcing member of 50 substantially pan-shape and defined by a body section secured to the bolster section, and integral wall sections outstanding from said body section, certain of said wall sections being respectively secured to the centersill and to the 55 bolster marginal section and the other of said wall sections operating to brace the first named wall sections.
21. In a railway car, the combination of centersill members uprightly disposed and spaced apart, an uprightly disposed bolster secured to 60
- said centersill members and extending outwardly on either side thereof, and a bottom member disposed beneath said centersill members and said bolster and secured thereto, said members having an integral centerplate portion and being provided with integral side bearing portions adjacent its ends beyond the centersills, said bottom member comprising a plate having a continuous reinforcing rib around its marginal edge, said ribs being disposed beyond and independently of the 10 center plate portion. 65
22. In a railway car, the combination of centersill members uprightly disposed and spaced apart, an uprightly disposed bolster secured to said centersill members and extending outwardly 15 on either side thereof, a bottom member disposed beneath said centersill members and said bolster and secured thereto and provided with integral side bearing portions adjacent its ends beyond the centersills, said bottom member comprising a 20 plate having a continuous reinforcing rib around its marginal edge, a centerplate portion positioned between and secured to said centersill members, and reinforcing cross ribs merging with said marginal rib and disposed beneath said centersill members to strengthen the centerplate portion. 25
23. In a railway car, the combination of a centersill embodying spaced upright members, a bolster extending transversely of said centersill 30 and outwardly on both sides thereof, a bottom member extending transversely at the centersill and outwardly beneath said bolster and plate, having a centerplate portion positioned between the centersill members, said bottom plate having 35 marginal and cross ribs for strengthening the area of said centerplate portion, integral side bearings on said bottom plate adjacent the ends thereof, and reinforcing ribs extending around the margins of the portions of said bottom plate 40 disposed beneath the bolster and merging with said side bearings. 45
24. In a railway car, the combination of a centersill, a transverse bolster, and a bottom member bridging the under side of said centersill extending beneath and secured to said bolster beyond the centersill on both sides thereof, said bottom member having side bearings adjacent its ends and a reinforcing wall associated with said side bearing and disposed at an angle substantially 50 normal to the plane of the body of said bottom member to throw the side strains on said side bearings toward the longitudinal axis of the car. 55
25. In a railway car, the combination of a centersill, a transverse bolster secured thereto and having its lower margins inclined upwardly in both directions from the centersill, a bottom member comprising a body section positioned beneath and secured to said centersill and bolster and conformed to the inclination of said lower 60 margins of the bolster, side bearings formed adjacent the ends of said bottom member, and transverse reinforcing ribs associated with said side bearings and disposed in planes at a normal angle to the inclination of said body section to 65 direct the strains on said side bearings toward the longitudinal center of the car.
26. In a railway car, the combination of a centersill, a transverse bolster secured thereto and having its lower margins inclined upwardly in 70 both directions from the centersill, a bottom member comprising a body section positioned beneath and secured to said centersill and bolster and conformed to the inclination of said lower margins of the bolster, side bearings formed adjacent the 75

ends of said bottom member, transverse reinforcing ribs associated with said side bearings and disposed in planes at a normal angle to the inclination of said body section to direct the 5 strains on said side bearings toward the longitudinal center of the car, and an integral extension projecting from the central portion of said body of said bottom member beyond the marginal rib thereof and secured to the centersill members.

27. As an article of manufacture, a reinforcing bottom member for the bolsters of railway cars, comprising a plate section having integral side bearing portions adjacent its ends and a marginal reinforcing rib extending around the edges of 10 said plate and merging with said side bearing portions, and cross-reinforcing ribs merging with said marginal rib for strengthening the central area of said plate section.

28. As an article of manufacture, an integral reinforcing bottom member for bolsters of railway cars comprising a body plate section having an integral depending marginal flange extending continuously around its edge and having integral side bearing members formed adjacent its 15 ends and having a centerplate portion adapted to be secured to the under side of a car centersill, integral reinforcing ribs transversely disposed on the under side of said body plate in the region of the centerplate portion, said reinforcing ribs being disposed beyond the center plate portion and an integral extension projecting from said body plate beyond the marginal reinforcing rib.

29. As an article of manufacture, an integral reinforcing bottom member for bolsters of railway cars comprising a body plate section having an integral depending marginal flange extending continuously around its edge and having integral side bearing members formed adjacent its ends and having a centerplate portion adapted to be 20 secured to the under side of a car centersill, integral reinforcing ribs transversely disposed on the under side of said body plate in the region of the centerplate portion, an integral extension projecting from said body plate beyond the marginal reinforcing rib, and a transverse reinforcement within said side bearings disposed in a plane 25 at a normal angle to the plane of the body plate.

30. In a railway car, the combination with centersills including upstanding web portions and 30 bolster sections on the opposite sides thereof secured to said web portions, said bolster sections having at their lower margins outstanding flange portions; of a combined center plate and bolster tie member disposed beneath the centersills and extending flatwise beneath the outstanding flanges of the bolster sections and secured thereto, said flatwise extending portions having depending integral ribs extending across the plane of the centersills and beneath the bolster diaphragms, said integral ribs being disposed independently of and to either side of the center plate.

31. In a railway car, the combination with an upstanding longitudinal centersill and upstanding transverse bolster members, said bolster sections 35 at opposite sides of the centersill inclining outwardly and upwardly from said centersill; a bottom member extending flatwise beneath said centersill and bolster members and inclining upwards to correspond to the upward inclination of the bolster members and secured to said last named members, said bottom member incorporat-

ing therein an integral center plate portion and having depending integral ribs extending across and beyond the centersill and beneath the upwardly extending bolster members, said integral ribs being disposed outwardly beyond the center plate and independently thereof.

32. As an article of manufacture an integral reinforcing bottom member for bolsters of railway cars comprising a body plate section having an integral center plate formed therewith and integral depending marginal flanges extending alongside of and beyond said center plate, said flanges being spaced from the center plate longitudinally of the centersills to reinforce the body of said center plate across the plane of the centersills.

33. As an article of manufacture an integral reinforcing bottom member for bolsters of railway cars comprising a body plate section having a center plate portion formed integrally therewith, 20 said body plate being adapted to be secured to the under side of a car centersill structure, said member having a flat body portion projecting to either side of the body plate section and adapted for attachment to bolster side sections, said body 25 plate being reinforced along the margins transversely across the centersill by integral depending ribs disposed outwardly beyond the center plate portion.

34. In a railway car, the combination with upstanding longitudinal centersills and upstanding transverse bolster members; of a bottom member extending flatwise beneath said centersill and bolster members, said bottom member incorporating therein integral center plate and side bearing members, said bottom member adjacent each end being formed with a depressed portion beyond the side bearings; and supplementary plates sandwiched between said depressed portions and the bolster members and adapted to provide continuity 30 of reinforcement beyond the limits of said bottom member.

35. In a railway car, the combination of upstanding longitudinal centersills and upstanding transverse bolster members, said bolster members 45 having outstanding lower marginal flanges, a bottom member extending flatwise beneath said centersill and bolster members and riveted to the said marginal flanges, said bottom member incorporating therein integral side bearing members, 50 said bottom member beyond the side bearings having plate members sandwiched between and riveted to the said bottom members and said marginal flanges, said plate members extending beyond the bottom members to provide continuity 55 of reinforcement beyond the limits thereof.

36. In a railway car construction, the combination with centersills and bolster sections on each side of the centersill, said bolster sections having outstanding lower marginal flanges; reinforcing means for the lower portion of the bolster, said means including a flat central body portion having integral center plate and side bearing members, said reinforcing means extending flatwise beneath and riveted to the bolster sections, 60 said central portion adjacent each side bearing having a plate overlappingly related thereto and extended outwardly beyond the ends of said central portion for cooperating engagement with the bolster sections.

ARGYLE CAMPBELL.
